UNITED STATES PATENT OFFICE.

MARIE ANTONIE MAHLER, OF LEIPZIG, GERMANY.

EDUCATIONAL APPARATUS.

Application filed January 27, 1926, Serial No. 84,015, and in Germany February 7, 1925.

My invention relates to means for assisting the blind in mathematical exercises and it has particular relation to devices which are formed from wire and provided with means permitting the insertion of such devices into supports.

At the present time the only means by which the blind may perform mathematical exercises are strings stretched between pins. Such method of instruction has been markedly insufficient, in fact so much so that it has been necessary to exempt the blind from examinations in mathematics, whereby many fields of science were barred to such persons.

My invention consists in representing mathematical values, products, signs, and the like, bodily with wire, the wire being provided with means to permit the insertion of such devices into elastic supports. Blind persons are, therefore, enabled to stick such devices into a support, for instance of felt, which latter serves as a working plane, whereon the mathematical devices may be arranged as required, and then removed, to perform a plurality of exercises.

Several elements are illustrated by way of example in the accompanying drawing, in which:

Figure 1 illustrates an element of my invention representing a dash line;

Fig. 2 illustrates an element representing a radical sign;

Fig. 3 illustrates a round bracket; and

Fig. 4 illustrates the manner in which certain devices, including another device constructed in accordance with my invention and representing a semi-circle, are used in solving a problem.

Referring generally to the drawing, it will be seen that representations of various indicia are formed of wire, the end portions of the latter being bent off from the intermediate portion in each case and being tapered to relatively sharp points. In this manner circles, semi-circles, ellipses, ellipsoid arcs, straight and curved lines of any desired size may be represented and constructed so that they can be placed together in any desired formation. Moreover, radical signs, square and round brackets, figures or characters, designation of

angles and the like may also be formed and provided with sharp points.

Referring particularly to Fig. 1 of the drawings, a wire 5 is provided with undulations, these undulations being positioned in a plane extending vertically and between the downwardly bent pointed ends, 6-6, i. e., in the plane of the sheet on which the drawing is illustrated. The crests of the wire are indicated at 7-7, while the valleys or depressions are indicated at 8-8. When such a device is felt by a blind person the crests or apices 7 are distinguished as being raised, whereas the depressions 8 are sensed as interruptions, with the result that the device as a whole represents to a blind person a broken or dash line.

Figure 2 represents a radical sign 13 provided with pointed ends 14 to permit its placement on a flexible or impressionable surface and Figure 3 illustrates a round bracket 15 having pointed ends 16.

In Fig. 4 I have shown the manner in which blind persons may utilize devices embodying my invention in the solution of a problem. Here a vertical line 11 is erected on the diameter 9 of a semi-circle represented by a wire 10 having an arcuate intermediate portion lying in a plane substantially at right angles to the pointed ends of the wire, and all the devices are stuck in a support 12.

It is to be understood that the above signs, and other devices, are only illustrative and that many other such values and products, in fact all the needed indicia whereby blind persons may practice mathematical exercises, may be formed in accordance with my invention. I therefore wish that the present showing be considered as illustrative only, and that the invention be limited only by the scope of the appended claims and the prior art.

I claim:

1. Devices for assisting blind persons in mathematical exercises comprising the representation of a dash line consisting of a wire having undulations therein extending in a vertical plane and said wire being provided with end portions bent at angles to permit the positioning of said devices on a working plane.

2. A device for assisting blind persons in mathematical exercises, comprising a wire formed with two end portions and a curved intermediate portion, said end portions being bent off from said intermediate portion and extending substantially parallel to each other whereby they may be inserted in a supporting

member to maintain said intermediate portion in fixed relation to said supporting member to convey to blind persons through their ¹⁰ sense of touch impressions of mathematical figures or like indicia.

In testimony whereof I affix my signature.
MARIE ANTONIE MAHLER.
